CLAIM

The ornamental design for a bearing, as shown and described.

DESCRIPTION

FIG. 1 is a perspective view of a first variant of a bearing. FIG. 2 is a lower rear perspective view of the bearing of FIG. 1.

FIG. 3 is a top plan view of the bearing of FIG. 1.

FIG. 4 is a front plan view of the bearing of FIG. 1.

FIG. 5 is a rear plan view of the bearing of FIG. 1.

FIG. 6 is a bottom plan view of the bearing of FIG. 1.

FIG. 7 is a left end view of the bearing of FIG. 1.

FIG. 8 is a right end view of the bearing of FIG. 1.

FIG. 9 is a perspective view of a variant of the bearing of FIG. 1.

FIG. 10 is a lower rear perspective view of the bearing of FIG. 9.

FIG. 11 is an upper perspective view of a variant of the bearing of FIG. 1.

FIG. 12 is a lower perspective rear view of the bearing of FIG. 11.

FIG. 13 is an upper perspective view of a variant of the bearing of FIG. 1.

FIG. 14 is a lower perspective rear view of the bearing of FIG. 13.

The broken line showing is for illustrative purposes only and forms no part of the claimed design.
